CLAIM

The ornamental design for a pet water or food storage unit with stowable bowl, as shown and described.

DESCRIPTION

This application is being filed contemporaneously with U.S. application Ser. No. 11/164,642. All of the material from U.S. application Ser. No. 11/164,642 that is essential to the claimed design is included herein. Any material in U.S. application Ser. No. 11/164,642 that is not present herein forms no part of the claimed design.

FIG. 1 is a perspective view of a pet food storage unit with stowable bowl embodying my design, with the handle, the end-mounted latches and clips for securing the lid to the container sidewall, the striations along the container sidewall, the mating edges of the container and dish sidewalls, and the end-mounted stop on the dish sidewall being shown in broken lines for illustrative purposes only and forming no part of the claimed design;

FIG. 2 is an opposite perspective view of the unit depicted in FIG. 1, with the recessed end section of the dish sidewall and the end cutout section of the container sidewall being shown in broken lines for illustrative purposes only and forming no part of the claimed design;

FIG. 3 is an end elevation view of the unit depicted in FIGS. 1 and 2;

FIG. 4 is a side elevation view of the unit depicted in FIGS. 1-3;

FIG. 5 is an end elevation view of the unit opposite that shown in FIG. 3;

FIG. 6 is a side elevation view of the unit opposite that shown in FIG. 4; and,

FIG. 7 is top plan view of the unit depicted in FIGS. 1-6.
